CLAIM

The ornamental design for a pusher device for bowling ball, as shown and described.

DESCRIPTION

FIG. 1 is a perspective view showing my new design for a pusher device for bowling ball, with portions of the handle broken away for convenience of illustration; FIG. 2 is a front elevational view of the device; FIG. 3 is a top plan view of the device; and FIG. 4 is an elevational view of the left side of the device.

FIG. 1.

FIG. 2.

FIG. 3.

FIG. 4.
